CLAIM

The ornamental design for human body detector, as shown and described.

DESCRIPTION

FIG. 1 is a front elevational view of human body detector showing my new design;

FIG. 2 is a left side elevational view thereof, the right side elevational view being a mirror image of that shown;

FIG. 3 is a top plan view thereof;

FIG. 4 is a bottom plan view thereof; and,

FIG. 5 is a perspective view thereof.
